UNITED STATES PATENT OFFICE.

LUTHER L. KNOX, OF BEN AVON, PENNSYLVANIA, ASSIGNOR TO KEYSTONE FURNACE CONSTRUCTION COMPANY, OF PITTSBURG, PENNSYLVANIA, A CORPORATION OF PENNSYLVANIA.

FURNACE.

No. 919,187.

Specification of Letters Patent. Patented April 20, 1909.

Application filed June 30, 1908. Serial No. 441,178.

To all whom it may concern:

Be it known that I, LUTHER L. KNOX, of Ben Avon, Allegheny county, Pennsylvania, have invented a new and useful Improvement in Furnaces, of which the following is a full, clear, and exact description, reference being had to the accompanying drawings, forming part of this specification, in which—

Figure 1 is a side elevation of a portion of the charging side of an open hearth furnace embodying my invention, with the necks connecting the regenerators with the slag pockets in section; Fig. 2 is a longitudinal section of the same; Fig. 3 is a plan view; Fig. 4 is a section on the line IV—IV of Fig. 3.

My invention has relation to improvements in furnaces, and is applicable to various kinds of furnaces, such as open hearth furnaces, melting furnaces, heating furnaces, etc., and is designed to provide means of novel and effective character for protecting the walls of the furnace and other parts thereof, or such portions thereof as may be necessary, from the more or less rapid destruction which ordinarily takes place in furnaces of this class.

My invention consists in the provision of novel means for water-cooling the various portions of the furnace walls which are most subject to this destructive action, such as the side walls, end walls, the roof, ports, and the up-takes.

The precise nature of my invention will be best understood by reference to the accompanying drawings, in which I have shown the invention as applied to an open hearth furnace, it being premised, however, that the details of construction and arrangement of the cooling means may be variously changed

by those skilled in the art without departing from the spirit and scope of my invention, and that the invention is equally applicable to other types of furnaces in the general class above stated.

In these drawings, the numeral 2 designates the side walls of the furnace, the wall at the charging side being provided with the usual charging doors 3 and mending door 4, and the opposite wall having the usual tap opening 5.

6 designates a portion of the hearth of the furnace, 7 the arched roof, 8 the gas up-take leading from the slag pocket 9, 10 the gas port leading from the up-take 8 into the furnace, 11 one of the air up-takes (shown in

dotted lines in Figs. 1 and 2), and which leads upwardly from the slag pocket 12, and 13 is the air port leading from said up-take 11 into the furnace.

In accordance with my invention, I provide the side walls 2 of the furnace each with a plurality of cooling boxes or castings 14, which extend vertically of the furnace walls, and which are placed side by side, said boxes extending upwardly from a point somewhat 60 above the normal level of the bath in the furnace through and above the tops of the side walls. Those boxes or castings which are immediately above the charging and mending doors are of course necessarily 65 shortened, and extend upwardly from a point shortly above these doors, as shown in Fig. 1. To receive these boxes or castings, the side walls of the furnace are provided with vertically extending pockets into which 70 the boxes may be placed, and from which they can be readily removed. To facilitate the construction of these pockets, the boxes are preferably made of a rectangular cross-section whose area bears a definite relation 75 to the sectional area of the bricks employed in the construction of the walls, so that the walls may be built to form these pockets without necessitating the cutting or breaking of the bricks. Suitable means are pro- 80 vided for the circulation of water through each of these boxes or castings, the cold water being taken in at the lower ends by means of suitable pipe connections 15, and the heated water being taken out at the up- 85 per ends by means of connections 16. Any suitable arrangement of circulating pipes 90 may be provided to which these connections lead.

The boxes 14 preferably not only extend 95 throughout the length of the wide walls of the hearth portion of the furnace, but are also provided in the side walls of the ports, as shown in Figs. 1 and 2. Resting on each side of the walls 2 and supported by the 100 skewback channels 17, is a hollow water-cooled skewback 18, which extends the full length of the furnace, being built in sections as shown in Fig. 1, so that it may be conveniently extended at the sides of the ports and 105 to the end of the furnace. These skewbacks support the roof arch 7, which is provided with a series of longitudinally extending cooling boxes or castings 19, which also extend the full length of the furnace, being

continued over the ports. These boxes or castings 19 are removably seated in pockets or recesses formed in the upper surface of the roof arch, and from which they are readily removable, being preferably made in sections of any convenient length.

The arch between the gas and air ports is formed in two sections 20 and 21, the outer section 20 over the gas up-take 8 being a solid brick arch, and the inner or nose portion 21 being removable and consisting of a hollow arched casting having skewbacks 22 which support the refractory roof 23 of the gas port, said casting also carrying the refractory covering 24 which forms the floor of the air port. This removable section 21 is seated between the solid brick arch 20 and a solid nose abutment 25. To provide for the removal of the section 21 the roof of the furnace over the air port is provided with an opening, which is preferably provided with a surrounding water-cooled frame or rim 26 and in which is seated a removable door 27 of refractory material and having a surrounding water-cooled frame 28. The circulating connections 29 for the hollow casting in the removable section 21 are carried downwardly through the door 27 and through a protecting pier 30 of refractory material. The hollow casting is preferably formed with a transversely extending compartment 31, into which the inlet pipe leads, and from which extend a series of pipes 32 into the interior of the casting, said pipes being arranged to discharge near the nose end of the casting, and the outlet pipe 29 being connected to the highest point of the casting below the inlet, as shown in Fig. 2.

33 designates transversely extending water-cooled boxes, one of which protects the abutment wall 25, and both of which form a support for the casting of the removable section 21. These boxes or castings 33 extend transversely into the furnace from both sides, as shown in dotted lines in Fig. 4.

The end wall of the furnace is provided with a series of vertically extending removable boxes or castings 34, which are similar in their arrangement to the boxes or castings 14 in the side walls, but which preferably extend downwardly or to a point near the slag pockets, and which may be extended downwardly sufficiently to also protect the walls of the slag pocket. These boxes 34 effectively prevent the cutting away of the rear walls of the gas up-take, without, however, exerting a sufficient cooling action to lower the temperature of the gas.

35 designates a cooling pipe, which extends transversely through the floor of the gas port and crossing the furnace, to prevent the cutting away of such wall and to also protect the walls of the up-takes.

It will be seen that I provide by simple and effective means for the water-cooling of

all portions of the furnace which are ordinarily most subject to the destructive action of the heat, this being effected for the most part by the arrangement of the vertically removable boxes or castings which can be readily seated in boxes provided therefor in the brick-work, and each of which is readily removable, so that it may be removed and replaced when necessary. The several boxes or castings are provided with any suitable arrangement of connections for circulating cooling fluid therethrough. It will also be seen that I provide for the ready removal and replacement of the nose portion of the arch between the gas and air ports, so that when this box is burned out it can be readily removed and replaced. The side walls of the furnace, the roof, the gas and air ports, and the up-takes, will all have their walls effectively cooled and protected by the arrangement of the cooling boxes as described.

It will be understood that the precise arrangement and form of the cooling box will necessarily depend in each case upon the size, character, &c., of the furnace, and will vary according to these circumstances; also that in some furnaces it may not be desired to provide all the portions thereof which I have herein shown and described with water-cooling means as in some cases the cooling means for the slag pots and regenerators can be omitted; also that cooling means may be provided for only those parts where they are considered most desirable for any particular case.

What I claim is:—

1. A regenerative reversing furnace, having its side wall formed with a plurality of open vertical pockets, arranged in parallel, spaced relation, and water cooling boxes or castings removably seated in said pockets, substantially as described.

2. A regenerative reversing furnace having its side and port walls formed with a plurality of open vertical pockets, arranged in parallel, spaced relation, and water cooling boxes or castings removably seated in said pockets, substantially as described.

3. A regenerative reversing furnace, having skewback channels at the upper portion of its side walls, and a series of pockets extending downwardly into the side walls behind the skewbacks, and water cooling boxes or castings seated in said pockets and removable from the top of the furnace, substantially as described.

4. A regenerative reversing furnace, having vertical open pockets in its walls, and cooling boxes removably seated in said pockets, said boxes having their inner vertical edges extending in lines at substantially right angles to the path of the gases past the said walls, substantially as described.

5. A regenerative reversing furnace, hav-

ing a roof of refractory material and provided with a plurality of longitudinally extending cooling boxes or castings embedded in the roof and spaced from each other by 5 the refractory material thereof, substantially as described.

6. A furnace having a roof provided with a series of longitudinally extending cooling boxes or castings seated in recesses in the 10 upper side of the roof and removable therefrom, said boxes being formed in sections, and extending over the hearth and also over the ports; substantially as described.

7. A regenerative reversing furnace, having 15 a roof of refractory material and provided with a plurality of longitudinally extending cooling boxes or castings embedded in the roof and spaced from each other by the refractory material thereof, 20 said boxes being formed into separate sections placed end to end, substantially as described.

8. A regenerative reversing furnace, having 25 a roof of refractory material provided with a plurality of spaced, longitudinally extending angular pockets, and a plurality of longitudinally extending cooling boxes or castings of angular form seating substantially flush within the said pockets, sub- 30 stantially as described.

9. A furnace having gas and air ports, a roof having an opening therein, and an arch separating the gas and air ports, said arch having a portion which is removable vertically through the opening in the roof of the 35 furnace; substantially as described.

10. A furnace having gas and air ports, a roof having an opening therein, and a refractory arch between said ports, said arch 40 having a nose portion vertically removable through the opening in the roof of the furnace; substantially as described.

11. A furnace having gas and air ports, a roof having an opening therein, and an arch between said ports, said arch having a nose 45 portion removable through the opening in the roof of the furnace and provided with means for circulating a cooling fluid therein; substantially as described.

12. A furnace of the character described 50 having an arch between its gas and air ports provided with a removable nose portion, the roof of the furnace above such portion being provided with a removable water-cooled portion or door; substantially as de- 55 scribed.

13. A furnace having gas and air ports, up-takes leading thereto, and cooling boxes or castings removably seated in vertical pockets in the back wall of the up-takes; 60 substantially as described.

14. A furnace having gas and air ports and an arch between said ports, said arch having a removable nose portion, and cooling boxes or castings extending below and 65 supporting said removable portion; sub- stantially as described.

15. A furnace having gas and air ports and an arch between said ports formed with a vertically removable section, said section 70 consisting of a body of refractory material having a water-cooled box or casting therein, said box or casting having an inlet compartment at one end and a plurality of pipes leading from said compartment and dis- 75 charging into the interior of the box or casting, together with circulating connections thereto; substantially as described.

In testimony whereof, I have hereunto set my hand.

LUTHER L. KNOX.
